CHAIR

Millard Fillmore Harty, Bloomfield Hills, and Arleigh C. Hitchcock, Muskegon, Mich., assignors to The Shaw-Walker Company, Muskegon, Mich., a corporation of Michigan

Filed June 16, 1969, Ser. No. 17,708

Term of patent 14 years

Int. Cl. D6—01

U.S. Cl. D15—1

FIG. 1 is a perspective view of a chair showing our new design;

FIG. 2 is a side elevational view thereof;

FIG. 3 is a front elevational view thereof;

FIG. 4 is a rear elevational view thereof;

FIG. 5 is a partial cross-sectional view taken along line 5—5 of FIG. 3; and

FIG. 6 is a cross-sectional view taken along line 6—6 of FIG. 2.

The side of the chair not shown is a mirror image of the side shown in FIG. 2.

We claim:

The ornamental design for a chair, as shown and described.
